AUTOMATIC STOKER

James A. Casey, Wilkes-Barre, Pa.

Application August 24, 1937, Serial No. 160,674

4 Claims. (Cl. 110—45)

This invention relates to automatic stokers and it has for its general object the provision of a stoker chassis adapted to be optionally employed with any of the several sizes of burner, to take coal by gravity from a hopper or by conveyor from a bin and to discharge ashes either into a pit or by means of one of several types of conveyor.

Another object of the invention is the provision of an automatic stoker consisting fundamentally of a burner, coal tube, coal receiver and fan in which the receiver is adapted to be connected to a gravity discharging hopper or to a conveyor leading from a remote bin.

A further object of the invention relates to orientable conveyors alternatively provided, for feeding coal from the bin to the receiver either by way of the top or bottom, with driving means for said conveyors.

Still another object of the invention in a stoker of the type described is the provision of a fan which while drawing the main part of its air supply for the fuel blast from atmosphere is at the same time in a recurrent air circulation system which draws air from the coal tube and discharges it into the main blast to the burner.

Another object of the invention relates to an automatic stoker including in combination with the burner element a rotating ash scraper including an element cooperating to continually remove the marginal accumulation of ash overlying the edge of the burner and the novel construction of ring upon which the ash scraper is mounted.

A further object of the invention relates to non-clogging driving means for the ash scraper ring.

Other objects of the invention relate to the automatic stoker as above described in a combination with alternative types of ash conveyor.

In the drawing throughout the several figures of which the same characters of reference have been employed to designate identical parts:

Figure 1 is a side sectional view of an automatic stoker embodying the features of the present invention;

Figure 2 is a plan view of the same partly in section;

Figure 3 is a plan view of the ash scraper ring parts being omitted;

Figure 4 is a side section showing details of construction of the ash scraper ring.

Referring now in detail to the figures, the numeral 1 represents a base having the conventional leveling means 2 and to which is secured the parts constituting the chassis 3. Said

chassis comprises a coal receiver 4 having a substantially horizontal coal tube 5 secured to the front end thereof and in communication therewith, the outer end of the coal tube being formed with an elbow 6 over which are mounted a plurality of coaxial rings 7 which normally rest freely upon one another with draft louvers 8 in between. Said rings progressively flare so that the number to be employed depends upon the diameter of the fire pot of the furnace in which the burner is installed.

A screw conveyor 9 extends through the coal tube 5 terminating substantially beneath the vertical axis of the burner and being suitably driven at its opposite end through a sprocket 10, the chassis being provided with an upwardly extending recess, housing said gear and which produces a hump 11 on the inside of the coal receiver 4. A fan 12 is suitably mounted with respect to the coal receiver 4, said fan taking in air centrally through a damper controlling opening 13 and discharging it peripherally through a conduit 14 which is not in communication with the coal receiver, but which communicates with an outer tubular casing 15 which surrounds the coal tube 5. The casing 15 terminates in an elbow 16 coaxial with the burner and surrounding the lowermost of the rings 7. Said elbow is formed with a wide inturned flange 17. To the inner edge of the flange 17 is bolted or otherwise secured an annular fitting 18 formed with an annular channel 19. In the channel is freely seated an inverted bell-shaped casting 20 which extends beyond the uppermost ring and terminates in a wide flange or collar 21 having an annular rabbet 22 forming a peripheral track on which rests the matching rabbet 23 of an outer rotating ash lip 24.

A ring 25 freely seats upon the outer peripheral portion of the flange 17 of the elbow 16, being rotatable thereabout. Said ring is provided with a bar 26 having an upstanding end 27 which moves concentrically with respect to the burner, and being attached to the ash lip 24, the latter rotating with said ring. The function of the rotating ash lip is to break the marginal portion of the ashes off from the ash heap on top of the fuel in the burner, and to let it drop by gravity into the pit 28. This is a continuous rotating operation whenever the stoker is operating.

The ring 25 seats on a flange 17 of the elbow 16 by means of a plurality of inwardly extending spaced lugs 29 which rest upon the flange 17. Said lugs have inwardly sloping top faces 30 which shed ashes which may collect upon them.

and side faces 38 which sweep ashes off of the flange 17. The ring 33 does not fit closely against the elbow 16, but is spaced therefrom by a narrow annular space 39, said space providing an annular passage for the ashes to drop through which are dislodged from the flange 17 by the lugs 36. It will be understood by the description of the ring 33 that it not only freely rotates, but also is capable of slight shifting motion in the plane of its rotation permitted by the space 39. Due to this free fit it is not necessary to machine the ring 33 so that it may be cheaply cast.

The ring 33 is provided with a lower peripherally extending flange 40 formed with gear teeth 41. (See Figure 2.) The ring 33 is rotated by means of a shaft 42 driven from the motor 43 and having a worm drive 44 in engagement with the gear teeth 41, said worm drive being in the form of a section of a screw propeller, the object 20 being to convey ashes away from the immediate vicinity of the gear teeth. This form of drive necessitates that the gear teeth be uni-directionally inclined and made in the form of knobs which freely fit the space between the spirals 25 of the screw, being driven thereby. It will be understood that the ring 33 is in position to be covered with ashes from time to time so that some special driving connection is necessary to prevent its becoming jammed with ashes. The 30 loose relation of the knob-like teeth 41 with the conveyor-shaped worm drive 44 ensures that there will be no jamming while the specific shape of the worm drive acts in effect to convey the ashes away from the gear connection and to keep 35 it clean. It will be understood that the worm drive 44 rotates in a direction to lift the ring 33 rather than in an opposite direction and thus minimizes the friction between the parts. It may happen that from time to time the ring 40 33 will chatter against its seat to safeguard which a lubricating cup 45 is provided with a tube 46 which opens on the seating face of the flange 17 and thus lubricates the bearing joint between the elbow and the ring 33. Experience has shown 45 that this lubricating cup 45 does not have to be attended more than once or twice in a season.

The air blast discharged from the periphery of the fan passes through the casing 15 upwardly between the burner rings on the one hand 50 and the wall of the elbow 16, the fitting 18 and the casting 20 on the other. The blast enters the burner through the annular cracks between the rings. In order to avoid back draft the lower rings are so shaped that the annular cracks 55 between them are inclined upwardly at their inner portions so that the entering air blows upwardly toward the burning surface of the fuel. Also the conduit 14 is placed into communication with the burner chamber below the bottom of the fuel body within the burner, by means of one or more small apertures 22 which equalizes the pressure below and within the burner chamber. The central fan inlet opening 13 is connected by 60 a manifold 23 with the chamber of the receiver 4 and incidentally with the coal tube 5. The fan draws its main body of air from atmosphere through the opening 24 in the manifold 23, but maintains a slight degree of sub-atmospheric pressure on the air within the coal tube 5. This assures that in the event of back pressure due to the explosion of combustible gases within the burner, said gases will be drawn through the coal tube through the opening 31 of the coal receiver 4, through the manifold 23 and back to the fan 70

to commingle with the blast which supplies draft to the burner.

Figure 1 shows that the coal is conveyed from a bin at some distance from the coal receiver 4. A pipe 25 is secured at an open boss 26 projecting from the lower portion of the receiver 4. Said pipe leads to the coal bin. A screw conveyor 27 extends through the pipe and is operatively connected to the sprocket 10. Said screw conveyor is preferably formed of sections. Three are shown in the drawing designated consecutively by the numerals 28, 29 and 30. The screws in these sections are of different pitch, that in the section closest to the bin being of steepest pitch and the pitch becoming less steep, and the spaces 15 between the helices widening in step by step stages as the conveyor approaches the coal receiver. This variation in the pitch causes the column of coal pushed through the pipe 25 to remain open and unjammed throughout the full 20 extent of the conveyor. It is clear that as the pitch of the helices becomes more inclined the coal will be moved with greater celerity, moving faster adjacent the receiver 4 than at the bin end of the conveyor so that the column of coal is 25 never jammed by the weight or mass of coal in the end of said column near the coal receiver. The nature of the pitch of the conveyor 27 as described also prevents clogging of the coal supply through the weight of the coal being lifted up the 30 inclined side of the hump 11. The flow of coal is further facilitated by the shape of the coal receiver which flares progressively from the outlet of the coal pipe 25.

As the coal cascades over the peak of the hump 35 11 down to the anterior of the conveyor 9, the particles will be relatively separate and any dust or small granules will be in a loose and easily dissipated condition. It would not do to have the back draft of the coal tube 5 impinge upon this cascading column of loose coal for the dust would thus become entrained in the blast of air fed to the burner and might clog the draft cracks between the rings 7. Consequently, the opening 31 by which the manifold 23 communicates with the coal receiver is placed close to the forward wall of the coal receiver and as far as possible from the region at which the coal cascades over the hump 11 so as to avoid entraining 45 loose dust and debris of the coal.

In operation, coal is conveyed from the bin by means of the screw conveyor 27, lifted over the hump 11 by the thrust of the said screw conveyor and cascades down upon the anterior end of the conveyor 9 within the coal tube 5. The 50 coal receiver 4 may become partially filled through the action of the conveyor 27. Coal is delivered by the conveyor 9 into the lower part of the burner chamber and pushed upward by the thrust of the conveyor spreading out as the 60 burner chamber flares, this preventing back pressure upon the conveyor 9. Combustion takes place adjacent the surface of the mass of coal in the burner the ashes falling upon the collar 21 and ash ring 47. Ashes are continually 65 scraped away by means of the bar 34 on the ash scraper ring 33. The fan draws in atmospheric air through the opening 24 in the manifold 23 and also draws in a small proportion of air 70 through the coal tube 5, the coal receiver 4, the opening 31 and by way of the manifold 23 the air is forced through the conduit 14, casing 15 and the air chamber surrounding the burner, entering the burner through the cracks of the 75

ring 1 and also entering below the mass of fuel in the burner through the apertures 22. As the ashes accumulate they may be removed from the pit 32 in any usual or convenient manner. 5 A plug 50 is provided in the bottom of the elbow 6 which may be removed permitting dust, etc., to be blown out through the port 74 which the plug 50 closes, said plug when screwed in butts against the boss 75 at the bottom of the elbow 6 lifting the elbow and rings, tightening the rings together. This is of great convenience in adjusting the rings after installing, for since the upper ring is supported by the bell-shaped casting 20 the bottom of which rests in a seal of 10 sand or etc., in the channel 19, it may be that the top ring will be unduly spaced from the rings below when the installation is first effected and before adjustment.

While I have in the above description disclosed 20 what I believe to be preferred and practical embodiments of my invention, it will be understood to those skilled in the art that the specific details and arrangements of parts as shown and described are by way of example and not to be construed as limiting the scope of protection of 25 the apparatus as claimed.

What I claim is:

1. Automatic stoker comprising a coal tube formed with an upturned elbow at one end, a 30 burner connected to said elbow comprising a plurality of spaced rings seated upon one another in inverted conical formation defining a fuel chamber, an air conduit surrounding said coal tube having an upturned elbow co-axial with 35 the elbow of said coal tube and terminating in a horizontal flange, a fitting secured to the inner margin of said flange leaving the outer margin exposed, said fitting having a channel, a flaring jacket having its lower end seated in said channel and its upper end connected to said burner 40

and terminating in an annular ash collar surrounding said burner, an ash lip seated on said collar and rotatable axially of said collar, a ring having inwardly extending spaced lugs freely surrounding the elbow of said air conduit with 5 an appreciable clearance space and resting upon said flange by means of said lugs, an arm fixed with respect to said ring and fixed to said ash lip for rotating the latter about said collar for dislodging the ashes overhanging said collar, 10 teeth on the periphery of said ring and means intermeshed with said teeth for driving said ring.

2. Automatic stoker as claimed in claim 1, the driving means for said ring comprising a shaft, a worm on said shaft formed as a screw conveyor 15 and the teeth on said ring being pins extending into the helical channel of said screw conveyor.

3. Automatic stoker as claimed in claim 1, the lugs on said ring having inclined side faces serving 20 to scrape ashes from the flange on which said lugs rest into the passages constituted by the clearance between said ring and elbow.

4. Automatic stoker comprising a coal tube formed with an upturned elbow at one end, a 25 burner connected to said elbow comprising a plurality of spaced rings seated upon one another in inverted conical formation defining a fuel chamber, the topmost ring comprising an annular collar with a peripheral rabbet forming a 30 track, an ash lip rotatably seated upon said track having its upper face substantially in the plane of the upper face of said collar and forming an outward continuation of said collar, a driving ring mounted adjacent the lower part of said 35 burner, and means arising from said driving ring and secured to said ash lip for rotating the latter with said driving ring.

JAMES A. CASEY. 40
